CLAIM

The ornamental design for a wheel linking piece, as shown and described.

DESCRIPTION

FIG. 1 is a perspective view of a wheel linking piece showing our new design;

FIG. 2 is a top plan view thereof, a bottom plan view being a mirror image; and,

FIG. 3 is a right side elevational view thereof, a left side, front, and rear elevational views being the same image. The broken lines shown are included for the purpose of illustrating portions of the article which form no part of the claimed design.
